UNITED STATES PATENT OFFICE.

JOHN KNIGHT, OF SAN FRANCISCO, CALIFORNIA, ASSIGNOR TO THE
PACIFIC INDICATOR COMPANY, OF CALIFORNIA.

STATION-INDICATOR.

SPECIFICATION forming part of Letters Patent No. 388,980, dated September 4, 1888.

Application filed May 4, 1888. Serial No. 272,834. (No model.)

To all whom it may concern:

Be it known that I, JOHN KNIGHT, of the city and county of San Francisco, State of California, have invented an Improvement in Station-Indicators; and I hereby declare the following to be a full, clear, and exact description of the same.

My invention relates to the class of indicators for use in the cars of street and other rail-
ways for the purpose of designating successive
streets or stations and presenting to view at
the same time any suitable advertising or display matter.

My invention consists, in connection with
the main drum or rollers of the indicating or
display ribbon, of the novel arrangement of
the driving-drum and the course or direction
of the ribbon, all of which I shall hereinafter
fully describe.

The object of my invention is to drive the
ribbon independently of the main drums or
rollers upon which it winds and from which it
unwinds, and to direct its course in suitable
manner.

Referring to the accompanying drawing,
the figure is a vertical section of my indicator.

A is the box or casing, designed to be set up
in the car in convenient position. It has the
front window, a, through which the ribbon B
may be observed. Fixed on a shaft, c, journaled
in the upper portion of the box, is a
drum or roller, C.

A shaft, d, is journaled in the lower portion
of the box, and upon the shaft is fitted the
lower drum or roller, D, which is made with
an open center, in which a coiled spring, E, is
seated, one end of the spring being attached
to the drum or roller and the other end to the
shaft. Upon the shaft of the upper roller, C,
is fixed a sprocket-pulley, c', and upon the
shaft of the lower roller, D, is fixed a sprocket-
pulley, d', and an endless chain, F, extends be-
tween and connects these sprocket-pulleys.
This is the general arrangement of parts as
heretofore constructed.

Mounted about the center of the box is the
drive-shaft g, having upon its end outside of
the box a sprocket-pulley, g', upon which a
chain, g'', operates, which said chain may pro-
ceed to any suitable source of power, hand or

otherwise. Upon the drive-shaft within the
box is the driving-drum G.

The following is the course of the ribbon B:
It is attached at its upper end to the upper
drum or roller, C, thence passing to and around
a guide-roller, x, thence up behind the win-
dow a to and around the guide-roller x', thence
to and back of the upper roller, C, thence to
and around a guide-roller, x'', thence to and
around the drive-drum G, thence over the
guide-roller x''' and down behind the window a
to the guide-roller x'', and thence up to its
point of attachment to the lower roller, D. To
begin the operation, before the ribbon is at-
tached to the lower drum or roller, D, said 65
roller is turned forward, so as to fully wind up
the spring E. Then the ribbon is attached.
Now, when started, the roller D moves back
and the tension of the spring E is directed to
keeping the ribbon taut as it winds up on roller
70 D, thus giving it the proper appearance, and
also enabling the drum G to drive it. The
chain-connection F between the upper and
lower shafts serves to effect the rotation of the
drums accurately in unison, so that neither 75
has any other function than that of winding
and unwinding the ribbon, no driving being
effected by them. When the ribbon is wind-
ing in the opposite direction, the winding up
of the spring keeps it taut. Thus the whole 80
driving is done by the independent drum G,
and without coming in contact directly or in-
directly with the rollers C D.

It will be observed that in the course which
the ribbon takes provision is made for expos- 85
ing both sides of it, for above the guide-rollers x
one side of the ribbon is presented, and
below the guide-roller x'' the other side is in
view. This gives an opportunity for printing
the names of streets or stations on one side 90
and any display matter on the other.

Having thus described my invention, what I
claim as new, and desire to secure by Letters
Patent, is—

1. In a station-indicator, drums or rollers 95
from and on which the indicating-ribbon un-
winds and winds successively, in combination
with a spring holding back on one of the
drums or rollers, whereby the ribbon is kept
taut, and an independent power-drum between 100

the upper and lower ribbon-drums for driving the ribbon, substantially as herein described.

2. In a station-indicator, an upper and a lower drum or roller for receiving and paying out the ribbon, in combination with an independent endless belt or chain connection between them, whereby they operate in unison, and an independent power-drum intermediate of the ribbon-holding drums for driving the ribbon, substantially as herein described.

3. In a station-indicator, the upper or lower drums or rollers and the indicating-ribbon between them, in combination with the pulleys on the shafts of the drums or rollers, the chain connecting them, and the independent power-drum on a shaft intermediate of the ribbon-holding drums for driving the ribbon, substantially as herein described.

4. In a station-indicator, the upper drum or roller, the lower drum or roller having an open center, the lower shaft, and the spiral spring connecting the lower drum or roller

with the lower shaft, and the indicating-ribbon connected with both drums or rollers, in combination with the independent chain connecting the shafts of the drums or rollers and the independent power-drum intermediate of the ribbon-drums for driving the ribbon, substantially as herein described. 25

5. A station-indicator comprising the box 30 having the window *a* and the several guide-rollers, as described, the upper drum or roller, *C*, and the lower drum or roller, *D*, and spring controlling it, the pulleys on the shafts of the drums or rollers and chain connecting them, 35 the independent driving-drum *G* between the ribbon-holding drums, and the indicating-ribbon *B*, substantially as herein described.

In witness whereof I have hereunto set my hand.

JOHN KNIGHT.
